Esq. ATTORNEY,

UNITED STATES PATENT OFFICE.

CORNELIUS F. LYNCH, OF NEW YORK, N. Y.

WINDOW SASH.

Application filed January 25, 1926. Serial No. 83,456.

This invention relates to improvements in window sash.

An object of my invention is to provide an improved form of window sash and assembly to afford the opening of the upper and lower sashes of the window by rotative movement while providing for the vertical upward and downward movement of the respective upper and lower sashes.

Pursuant to a preferred form of my invention, the window sash comprises an upper sash and a lower sash which are respectively mounted in separate grooves or equivalent in the exposed lateral faces of the window casing and equipped with sash cord and weights or equivalent pursuant to the usual practice to effect the vertical upward and downward movement of the respective upper and lower sashes within the window casing. The upper sash carries the glass for the same in a frame identified herein as the upper glass frame, which is pivotally mounted at its opposite sides to swing about a horizontal axis. The abutting faces of the respective upper, lower and lateral strips of the upper glass frame and the upper sash are arranged relative to one another to attain automatic locking of the upper glass frame when the upper sash is in its closed position. Similarly, the glass of the lower sash is mounted in a frame identified herein as the lower glass frame, which is pivotally supported in the lower sash to provide for rotative movement on a horizontal axis, and the abutting upper, lower and lateral strips of the glass frame and of the lower sash are related to one another to provide for the automatic locking of the parts when in their closed position.

Further features and objects of the invention will be more fully understood from the following detail description and the accompanying drawings, in which

Fig. 1 is a perspective view showing a form of my invention and illustrating the glass frame of the lower sash in an open position;

Fig. 2 is a central sectional elevation of Fig. 1, taken on a greatly enlarged scale; showing the upper glass frame in its open position and the lower glass frame in its closed position;

Fig. 3 is a sectional elevation on line 3—3 of Fig. 2;

Fig. 4 is an exploded perspective view of 55 certain detail parts of my invention;

Fig. 5 is an exploded view in perspective, showing a manner of assembly of a glass frame in its sash and the interconnecting pivotal mounting members; and 60

Fig. 6 is a perspective view showing the stage of final assembly of the parts illustrated in Fig. 5.

Referring to Fig. 1, the window casing 10 may be of the regulation or any approved form. The upper sash 11 is shown in Fig. 1 in its raised position. The lower sash 12 is shown in Fig. 1 in its lowered position and its glass frame 13 in an open position by swinging the same. The view illustrated in Fig. 1 is that from the interior of the building, the sill 14 representing the inside sill of the window casing 10.

The manner of associating the upper sash 11 and the lower sash 12 to provide for the vertical upward and downward movements of the same may be as desired; I have illustrated in the drawings the common form of such arrangement including the sash cord 15, see Fig. 2, one end 16 of which is secured to the outer face of the right-hand side 17, see also Fig. 1, of the lower sash 12, then extends upwardly over the pulley 18, thence downwardly within the hollow interior of the window casing 10 to be connected 75 to the sash weight 19. The guide strip 20 is located between the respective edges of the inner and outer faces of the outer strip 21 and inner strip 22 of the respective lateral sides of the window casing 10 to provide 80 for the two usual grooves for guiding the upper sash 11 and the lower sash 12 respectively.

In Fig. 2, the upper glass frame 23 is shown in its rotated and open position. The glass of the upper frame 23 is indicated at 24 and is inserted in its frame 23 in the regulation or other approved manner. The pivotal mounting of the frame 23 in its upper sash 11 may be effected in any desired manner. In the forms of my invention illustrated in the drawings, I have employed the simplest form of such pivotal mounting comprising the pivot plate 25 provided with the pivot pin 26 and the complementary socket plate 27 is provided with a socket opening 28 for receiving the pivot pin 26. The pivot plate 25 is secured by screws 29

to the oppositely disposed lateral strips 30, 31 of, say, the glass frame 23 and the socket plate 27 is secured by the screws 32 to the oppositely disposed lateral strips 33, 34 of the upper window sash 11.

Such complementary pivotal mounting plates serve also as wind jamb parts for the extents of the lengths of such plates and coact with other parts serving as auxiliary wind 10 jams for the remainder of the height of the upper sash, as is set forth more fully herein-after.

A similar arrangement of complementary pivotal mounting plates, and serving also as 15 wind jamb parts, is provided for the mounting of the lower glass frame in the lower sash, and like parts are designated by like reference numbers with the suffix "a."

Preferably, the upper glass frame 23 is related to its sash 11 to attain automatic locking of the glass frame 23 upon the movement of the glass frame 23 to its closed position. Such locking relationship is had by the provision of the offset or angular faces between 20 either the upper or the lower strips of the glass frame 23 respectively relative to the upper and lower strips of the upper sash 11; in the most preferred form of my invention such locking relation is provided at both of 25 the locations named. One form of such locking relation is effected by providing the extension 35 projecting upwardly of the outer portion of the upper strip 36 of the glass frame 23 which when the glass frame 23 is 30 in its closed position is received within a correspondingly cut-away recess of the upper strip 37 of the upper sash 11. Similarly, the lower strip 38 of the upper glass frame 23 is 35 cut away as indicated at 39 to receive the upward extension 40 of the lower strip 41 of the upper sash 11. It will be observed that the oppositely disposed lateral strips 28, 29 of the upper glass frame 23 may be of the full width of the upper and lower strips 36, 40. 45 38, and in this instance the upper strip 36 is shown as the wider strip.

It will be noted in Fig. 2 that the upper sash 11 has been moved downwardly somewhat from its uppermost position to clear the 50 extension 35 of the upper stop strip 42 of the window casing 10. When it is desired to close the upper sash, the glass frame 23 is swung in the opposite direction, namely in counter-clockwise rotation, to bring the 55 aforesaid interlocking strip parts to their mutually locking positions, whereupon the upper sash 11 is pushed upwardly, the aforesaid extension 35 being received between the upper strip 37 of the upper sash 11 and the 60 stop strip 42 of the window casing 10, thus locking the parts of the upper sash 11 and of the upper glass frame 23 in their closed 65 positions.

The securement of the aforesaid parts of 65 the upper sash to the upper glass frame may

be had by the regulation or other approved form of window lock such as is illustrated in the drawings and comprising the catch member 43 and the pivotal cam member 44. However, in carrying out my invention, the 70 catch member 43 is secured by screws or the like to the lower strip 40 of the upper sash 11 and the pivotal cam member 44 secured by screws or the like to the upper strip 45 of the lower sash assembly.

The lower sash and its glass frame are similarly arranged in self-locking position when the upper sash and the lower sash are in their mutually closed and locked position. The glass of the lower sash is indicated at 46 80 and is mounted in a frame comprising the upper strip 45, the oppositely disposed lateral strips 47, 48 and the lower strip 49. One form of such mutually locking relation for the assembly of the lower sash parts is had 85 by locating the upper strip 52 of the lower sash 12 intermediate the lower strip 40 of the upper sash 11 and the upper strip 45 of the lower glass frame. In such arrangement the pivotal cam member 44 is secured to the 90 upper strip 45 of the lower glass frame.

In the embodiment illustrated in the drawings, the lower glass frame is mounted to swing by turning the same in clockwise direction as is indicated by the arrows 50. The 95 pivotal mounting, as above indicated, is similar to that illustrated in Fig. 4 relative to the pivotal mounting of the upper glass frame 23. In such arrangement, the lower strip 49 of the lower glass frame is rabbeted 100 relative to the lower strip 51 of the lower sash 12, the extension 49^a of such rabbeted strip 49 extending on the outer face of the lower strip 51 of the lower sash 12.

The lower window sash 12 is suspended 105 from sash cords and counter-weighted similarly to the upper window sash 11, and like parts are designated by like reference numbers.

The function of preventing leakage of air, 110 rain and dust served by the complementary pivot pin and socket plates is afforded by providing the central circular portions of each of one-half thickness and the oppositely extending arm portions of each of double 115 thickness, the arm portions being displaced relatively to one another to be disposed side by side and of one-half of the width of the respective lateral strips of the upper and lower glass frames, when the upper and lower 120 glass frames are in vertical or closed position.

The auxiliary wind jamb parts comprise the oppositely disposed jamb strips, see Fig. 5, designated 55, 56, both disposed on a 125 lateral strip, say, the lateral strip 53 of the lower sash 12 and spaced apart to provide for the clearance required for the complementary pivot and socket members 25^a, 27^a. Similar strips 55, 56 are provided for the 130

opposite lateral strip 54 of the lower sash 12, and likewise for the corresponding oppositely disposed lateral strips of the upper glass frame.

5 Complementary strips are correspondingly applied to the oppositely disposed lateral strips 47, 48 of the lower glass frame and are designated 57, 58.

Such or equivalent arrangement of complementary pivotal pin and socket members affords a simple form of assembly of each glass frame within its sash and similarly a simple form of removal of each glass frame from its sash. This is illustrated in 10 the exploded view shown in Fig. 5 and a simplified form of assembly is had by mounting the oppositely disposed pivot plates 25^a, 25^b, on the oppositely disposed lateral strips 47, 48, of the lower glass frame, then loosely placing the respective socket plates 27^a with the respective pivot pins 26^a, 26^b within the respective sockets 28^a, and bodily moving the lower glass frame to position the respective sets of pivot plates 25 and socket plates within the spaces between the respective jamb strips 55, 56, then turning the lower glass frame to a horizontal position as indicated in Fig. 6, thus permitting the positioning of the respective socket plates 27^a to afford access to the screw openings in the same and enable the screws 32^a to be turned by a screw driver or the like and seated in proper position, as above indicated.

35 The lower sill is preferably provided with a stop strip or equivalent for locking the frame of the lower glass 46 when the lower glass frame and the lower sash 12 are in their lowermost positions. As is illustrated in Fig. 2, such stop for the sill 60 may be formed by cutting away a portion 61 of the upper surface of the outer sill 60 to provide a depression for receiving the lowermost portion 62 of the lower strip 49 of the lower glass frame. Accordingly, upon closing the upper glass frame 23 and raising the upper sash 11 to its uppermost position, whereby the stop strip 42 disposed upwardly of the window casing 10 locks the upper glass frame 23 and the upper sash 11, and the depression 61 of the sill of the window casing 10 locks the lower glass frame and the lower sash 12, the closing of the lock 43, 44 locks all the parts of the upper sash, its upper glass frame, the lower sash and the lower glass frame in common in their respective closed positions.

Such locking relation of the lower glass frame and the lower sash also precludes the 60 "jimmying" of the lower sash or the lower glass frame when the parts of my improved window are in their respective locked positions.

65 My invention affords many advantages in its use for ventilating to varied positions of

the respective upper and lower glass frames, the cleaning of the glass of the upper and lower sash and the renewal or repairs of the glass. When it is desired to obtain ventilation, say for the upper glass 24 only, the 70 upper sash 11 is slightly lowered, whereupon the upper glass frame 23 may be turned to any desired set position. Such ventilation is effected without movement of the lower sash and effects such ventilation from the top of 75 the window, as is most desirable in certain circumstances. When it is desired to ventilate through the lower sash, the lower sash is slightly raised to clear the extension of the faces of the depression 61, thus permitting 80 the lower glass frame to be turned as desired. Such ventilation through the lower glass may be had independently of the ventilation through the upper glass, or the ventilation may be had by tilting both the upper 85 glass frame and the lower glass frame and each to independent extents.

The cleaning of the glass of the upper sash and the glass of the lower sash is attained wholly from the interior of the window casing, thus obviating the dangers to life and limb of present day window cleaners and eliminating the liabilities entailed in present day window cleaning methods.

When it is desired to replace a broken 90 glass, the operation of replacement is attained without removal of the glass frame, if desired, and wholly from the interior of the window casing. It will also be apparent that either glass frame may be removed from 95 its sash, if preferred, for the purpose of replacing a broken glass, or for other purposes.

The construction of my improved window also affords a ventilation through the window under the circumstances of rainy 100 weather as by ventilating through the lower sash, by reason of the lower sash as above described, then turning the lower glass frame, whereby the lower portion of the 105 lower glass frame is positioned above the outer sill 60, thus preventing the rain from striking the outer sill 60 and rebounding through the opening in the lower sash and into the 110 room.

The form of my invention illustrated in the drawings may be comprised wholly of parts made of wood or like material, but it will be observed that the parts of the upper sash, its glass frame, the lower sash and 115 its glass frame may be of steel or other suitable material and of appropriate thicknesses, somewhat reduced as compared with the dimensions indicated in the drawings, but of the same relation and arrangement and mutually co-acting parts as hereinabove described.

Whereas, I have described my invention by reference to specific forms thereof, it will be understood that many changes and 120

modifications may be made without departing from the spirit of the invention.

I claim:

1. The combination of an upper sash, an upper frame pivotally mounted in said upper sash, the upper edge of said upper frame extending substantially to the upper edge of said upper sash when said upper frame is in its uppermost position, a sheet of transparent material disposed in said upper frame, a lower sash, a lower frame pivotally mounted in said lower frame, and means for locking said upper and lower sashes and said upper and lower frames when in closed positions, 10 said locking means comprising two parts, one part secured to a lower portion of said upper sash and another part secured to said lower frame.
2. The combination with a window casing having a stop strip, of a sash arranged to be mounted for vertical upward and downward movement in said window casing, a sheet of transparent material, a frame carrying said sheet of transparent material and means 20 for pivotally mounting said frame in said sash, said frame having an extension disposed in locked position relative to said stop strip when said frame and said sash are in their closed positions.
3. The combination with a window casing having a stop strip, of a sash arranged to be mounted for vertical upward and downward movement in said window casing, a sheet of transparent material, a frame directly carrying said sheet of transparent material and means for pivotally mounting said frame in said sash, said frame having an extension disposed in locked position relative to said stop strip when said frame and 30 said sash are in their closed positions.
4. The combination with a window casing having a stop strip, of an upper sash, a lower sash, and frame means for pivotally mounting a sheet of transparent material in one of said sashes, said frame means comprising a portion disposed in locked relation with said stop strip when said frame and its sash are in their closed positions.
5. The combination with a window casing having a stop strip, of an upper sash, a lower sash, frame means for pivotally mounting a sheet of transparent material

in one of said sashes, said frame means comprising a portion disposed in locked relation with said stop strip when said frame and its sash are in their closed positions and means for locking said upper sash, said lower sash and said frame means in common in their respective closed positions.

6. The combination with a window casing having an upwardly disposed stop strip and a downwardly disposed stop strip, of an upper sash, frame means for pivotally mounting a sheet of transparent material in said upper sash, said frame means having an upper portion disposed in locked position relative to said upwardly disposed stop strip when said upper sash and said frame means are in their uppermost position, a lower sash and a lower frame means for pivotally mounting a sheet of transparent material in said lower sash, said lower frame means being provided with a portion disposed in locked relation with said downwardly disposed stop strip of said window casing when said lower sash and said lower frame means are in their lowermost position.

7. The combination with a window casing having an upwardly disposed stop strip and a downwardly disposed stop strip of an upper sash, frame means for pivotally mounting a sheet of transparent material in said upper sash, said frame means having an upper portion disposed in locked position relative to said upwardly disposed stop strip when said upper sash and said frame means are in their uppermost position, a lower sash, a lower frame means for pivotally mounting a sheet of transparent material in said lower sash, said lower frame means being provided with a portion disposed in locked relation with said downwardly disposed stop strip of said window casing when said lower sash and said lower frame means are in their lowermost position and locking means for locking said upper sash, said upper frame means, said lower sash and said lower frame means in common in their respective closed positions, said locking means comprising an element carried by said upper sash.

In testimony whereof I have signed this specification this 13th day of January 1926.

CORNELIUS F. LYNCH.
